MOLDABLE COIN COLLECTION BOX WITH
TRANSLATABLE COVERRobert L. Keeler, Chicago, Ill., assignor to The
Salvation Army, Chicago, Ill., a corporation of
Illinois

Application February 5, 1949, Serial No. 74,787

5 Claims. (Cl. 232—1)

1

The present invention relates to theftproof coin collection boxes, and is particularly concerned with the provision of an improved collection box which is simple in structure so that it can be made out of molded plastic; but which is also adapted to be locked in closed condition, and which has suitable provision so that coins or bills which are inserted therein cannot be removed through the entrance slot except with considerable difficulty.

One of the objects of the invention is the provision of an improved coin collection box, which is provided with a combined handle and cover so constructed and mounted relative to the box so that the cover may be locked by means of a single hasp and a padlock.

Another object is the provision of an improved collection box of the class described, the cover of which is of such shape that it is slidably mounted in one end of the collection box, and the cover of which is provided with suitable guides above and below so that it cannot be removed except by a movement of translation; and the cover may be locked in place by means of a single padlock or other locking device.

Another object of the invention is the provision of an improved coin collection box, which is so provided with baffles adjacent its coin opening that any coins which might light upon this opening, when the box is upside down, are deflected away from the opening and prevented from emerging through the coin slot.

Another object of the invention is the provision of an improved coin collection box, which is safe and secure, durable, easily locked with a single locking device, capable of economical manufacture and which presents serious difficulties to the removal of the coins or bills except through the authorized opening of the box.

Other objects and advantages of the invention will be apparent from the following description and the accompanying drawings, in which similar characters of reference indicate similar parts throughout the several views.

Referring to the single sheet of drawings accompanying the specification,

Fig. 1 is a side elevation of a collection box embodying the invention;

Fig. 2 is an end elevation taken from the handle end;

Fig. 3 is a vertical sectional view taken on the plane of the line 3—3 of Figure 2, looking in the direction of the arrows;

Fig. 4 is an inside elevational view of the cover;

Fig. 5 is an end elevational view of the open end of the box with the cover removed; and

2

Fig. 6 is a top plan view of cover with handle broken away drawn on a smaller scale.

Fig. 7 is a view in perspective of a U-shaped spring, shown inverted, to illustrate how its legs 67 may be pinched together at 68 on what will be the lower side, to let coins in, but prevent their exit.

Referring to Figures 1, 2 and 5, 10 indicates in its entirety the collection box which consists of an open-ended box 11 for slidably receiving a cover 12. The box 11 is preferably shaped in end elevation substantially like a shield, as shown in Figures 2 and 5, so that the shape of the box will be distinctive and indicative of the organization for which the collection is made. Thus the top of the box consists of a pair of outwardly concave wall portions 13 and 14 joined along a central longitudinal ridge 15.

The ridge 15 is provided with a longitudinally extending slot 16, and the slot extends out the open end 17 of the container 11, but is diminished in size by means of a slot closure 18 which is carried by the cover 12 and which fits in the open end of the slot.

The length of the slot 16 is such that it extends substantially past the middle of the container, so that when the open end of the slot is closed by the slot closure 18 the remaining open portion of the slot 16 is centrally located between the ends of the container 11.

The container 11 also includes the left end wall 19 and the two side walls 20, 21, which are joined together along the line of a relatively blunt ridge 22, and the side walls 20, 21 are concavely curved at their upper portions 23, 24.

Below these inwardly curved portions 24 the side walls have outwardly convex portions 25, 26 which extend downward toward each other to form the bottom 27, where the two portions 27 of the bottom join at the ridge 22.

The container 11 is preferably molded out of one integral piece of initially plastic material, such as a phenolic condensation compound or any modern moldable plastic. The bottom of the container 11 is preferably formed at its open end with a pair of laterally projecting transverse wall portions 28, 29, each of which is integrally joined to the container and to the opposed side wall portions 30, 31. This forms a box which is open when the cover is removed on its top, front and bottom, but is closed at its rear.

The bottom rib 32 of the container forms an integral part of the container and has an outwardly projecting hasp formation 33, which is provided with a through aperture 34 for receiving a padlock 35.

The cover 12 has an upwardly extending and downwardly open rectangular slot 36 in its lower edge 37 for receiving this hasp formation 33. On either side of the hasp formation 33 the container 11 is formed with recesses for rectangular sockets which are bounded by the walls 30, 28 and hasp formation 33, and by the walls 29, 31 and hasp formation 33.

These sockets are open upwardly, downwardly and forwardly, and the side walls 30, 31 and hasp formation provide guide surfaces for guiding the cover into place. In addition to the inner surfaces of these walls serving as guides, the two walls 30, 31 are provided with rectangular inwardly extending slots 38, 39 for receiving complementary rectangular ribs 40 carried by the cover.

The upper walls 13, 14 of the container 11, which are provided with the slot 16 at the ridge 15, are also preferably provided with a pair of depending baffles 41, 42, one on each side of the slot 16, the inner and opposed surfaces 43 of these baffles being flush with the edges of the slot.

Opposed surfaces 43 of baffles 41, 42 may have opposed grooves 65 extending out from the open end of the container to receive U-spring 66 (Fig. 7), which, when inverted and inserted in grooves 65, permits money to enter, but not to pass out again.

The baffles are preferably slightly longer than the slot, and one baffle 42 is preferably wider than the other, for the purpose of preventing coins from balancing on the two baffles when the container is upside down. Both baffles are preferably beveled at their outer lower edges, as indicated at 44, thus providing a relatively sharp edge on each baffle and giving the baffles such formation that coins are deflected away from the slot 16, if they hit the edge of the baffles.

The beveled baffles of unequal width tend to make it difficult to remove coins or bills from the container by those who are unauthorized and who do not have the key to the padlock.

The cover 12 is also preferably molded of a modern plastic, and it is provided with a substantially flat or plane body 45. This body has an outline which corresponds substantially to the interior of the container 11, and the body is preferably made substantially thicker at the portion 46 adjacent its edge. The thicker edge portion so strengthens the body that the main body portion 45 may be thinner to save material.

In addition to its general correspondence with the interior outline of the container 11, the cover 12 is provided with a depending rectangular formation separated by the slot 36 into two substantially square portions. These square portions also comprise a flat front body portion 47 which is flush with the front of the body portion 45, and each body portion 47 has a rearwardly projecting rectangular wall 48.

The space 49 inside the walls 48 is hollow for the purpose of saving material, and the box-like portions 48 actually serve as depending and inwardly extending guide lugs for guiding the cover as it slides into the container 11, and for providing a keeper which would engage the padlock 35, if it were sought to remove the cover while the padlock is on the hasp 33.

The box-like formations 48 slide into the recess between the wall 30 and hasp 33, and the wall 31 and hasp 33, while the ribs 40 slide into the slots 38. Thus the lower edge of the cover must be attached to the container by a

movement of pure translation without any pivotal movement.

Adjacent its upper edge the cover 12 is provided on its rear side with a pair of trapezoidal guide flanges 50, which are beveled at 51 on their lower edges and which terminate short of the end of the slot 16. These guide flanges may form an integral part of the cover and are provided with straight rear edges 52 and straight upper edges 53. The straight upper edges 53 are adapted to engage the inside surfaces 54 of the top portions 13 and 14, when the cover is moved into place.

In addition to the guide flanges 50, the rear side of the cover carries the slot closure flange 18, which may be of the same shape, but which extends higher so that its upper edge 55 is flush with the upper ridge 15 of the container 11. The slot closure flange 18 fills the open end of the coin slot 16 and reduces the length of this slot so that the open portion is located midway between the ends of the container 11.

The slot closure flange 18 also serves to guide the cover into position by means of a sliding movement, and the outer boundary 56 of the cover is a substantially tight sliding fit in the inner boundary of the walls of the container 11.

The thickness front to back of the box formations 48 is such that when they are located in the recess against the rear walls 28, 29, the body 45 of the cover has its outer surface flush with the edge 57 of the open end of the container 11. Thus the depending lugs which are formed by the box formations 48 serve to limit the inward movement of the cover at this end.

The cover 12 is also preferably formed with an integral handle 58, and this handle may consist of a curved or arcuate integral piece of the same material, integrally joined to the body 45 of the cover on its outer face and preferably located toward the upper side of the cover.

The handle may be formed with a multiplicity of partially cylindrical depressions 59, extending inwardly from either lateral edge of the handle; but terminating short of a centrally located rib 60 so that the handle may be grasped more firmly without slipping.

At its upper end the handle 58 is integrally secured to the cover body 45 at the upper ridge 15 of the container, and the handle preferably has a top guide flange 61 which overlaps the top of the container and extends downwardly on both sides of the curved walls 13 and 14. At this point the handle is preferably provided with a diagonal slot 62, extending into the back of the cover for receiving the edge parts of the top walls 13 and 14.

The base of these slots 62 serves as a stop surface for preventing further inward movement of the cover at the top, and thus the top of the cover is held flush with the surface of the edge 57 of the container 11.

The operation of my coin collection box is as follows:

The cover may be removed from the container by first unlocking the padlock and removing the padlock from the hasp 33, then the cover is pulled outward so that it slides out of the end of the container. In order to replace the cover, this is done with a reverse sliding motion, the cover sliding into the container in such manner that the top guide flanges 50 slide under the top of the top wall and the box formations 48 slide in between the walls 30 and 31.

When the cover is closed the padlock part may

be inserted in the aperture 34, and although the padlock confines only one end of the cover the cover cannot be removed because it will bind in the container if tilted in any way.

The ribs 40, sliding in slot 38 at the bottom of the container, also serve to make the cover move in a straight line and effectively prevent removal of the cover although it is locked with only one padlock.

The depending baffles on both sides of the coin slot serve to prevent the removal of coins through the coin slot, and tend to deflect the coins away from the coin slot if the container is turned upside down.

The present device may be manufactured by molding and may, therefore, be produced at a low cost so that such collection boxes may be used without greatly increasing the cost of collecting funds. While it is true that such a collection box can be broken, if it is desired to do so in stealing the contents, such boxes are placed in the custody of people who would not resort to the breaking of the box and, therefore, the boxes provide sufficient protection against theft in the routine collection of funds.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a coin collection box, the combination of a cover member provided with a handle on its face, with a container, the said container having an interior outline complementary to the exterior outline of the cover so that the cover may be inserted in the container, the said container having a coin slot in one of its side walls, and guide means cooperating between the cover and the container so that the cover must be moved in a motion of translation to slide into the container during its closure or to slide out of the container during its opening, the said cover supporting a centrally located flange slidably mounted to be inserted in

the coin slot, and the coin slot being open toward the cover side of the container to receive said flange.

2. A coin collection box according to claim 1, in which the coin slot is bordered by a pair of inwardly projecting baffles, spaced from each other, to pass money inward, but to interpose difficulty to its passage outward by reason of their projection into the container, and in which said baffles are of unequal width and beveled on their outer edges to deflect money away from the slot on the inside of the container.

3. A coin collection box according to claim 1, in which the walls of the coin slot are recessed to receive a spring, and a spring in said recess, having flat legs, twisted toward each other on the inner side, to be sprung apart by passage of coins inward, but presenting closed edges to the passage of coins outward.

4. A coin collection box according to claim 1, in which said guide means comprises a pair of plane parallel walls carried by the container, engaging opposed plane parallel walls carried by the cover, the said engaging walls having a tongue and groove formation extending in the direction of cover movement.

5. A coin collection box according to claim 1, in which said guide means comprises a tongue and groove connection between parts on one side of the container and cover, and inwardly projecting flanges on the cover having their edges engaging the inside wall of the container as the cover moves.
